UNITED STATES PATENT OFFICE.

SAMUEL M. RIKER, OF CHESTER, NEW JERSEY.

CROCHET NEEDLE.

1,409,580.

Specification of Letters Patent. Patented Mar. 14, 1922.

Application filed December 29, 1920. Serial No. 433,818.

To all whom it may concern:

Be it known that I, SAMUEL M. RIKER, a citizen of the United States, residing at Chester, in the county of Morris and State 5 of New Jersey, have invented certain new and useful Improvements in Crochet Needles; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 The present invention relates, generally, to improvements in needles; and, the said invention has reference, more particularly, to a novel construction of crochet-needle, the shank or main stem of which is provided at 20 a point between the working point or tip and the opposite end of the shank or stem, with a pivotally disposed finger-receiving member or guard, arranged to receive the operator's index finger, for the purpose of 25 properly and effectively holding the needle in its operative relation to the hand, as well as to the work, and the pivotal arrangement of the finger-receiving member or guard permitting the proper positioning of the 30 needle upon the index finger of either the right or left hand, so that the crochet-needle may be effectively employed by either a right-handed or left-handed person, as may be desired.

35 The present invention, therefore, has for its principal objects to provide a novel and simply-constructed crochet-needle, upon the shank or stem of which is pivotally mounted a finger-receiving member or guard, with 40 a view of providing a simple means for maintaining the proper position of the needle to the hand of the operator, and also dispensing with the usual tiring effect, due to the fact that the shank or stem of the 45 usual needle has to be firmly held between the thumb and forefinger of the operator, and, furthermore, the pivotal arrangement of the finger-receiving member or guard permitting the use of the needle, effectively, by 50 either a right-handed or left-handed person.

The present invention has for a further object to provide in connection with the shank or stem of a crochet-needle, a finger-receiving member or guard of the general 55 character hereinafter more particularly set forth, which may be detachably mounted

upon the shank or needle, so that if desired, the finger-receiving member or guard can be removed from the shank or stem of the needle, and that the latter can then be used 60 in the manner of the usual and ordinary crochet-needle, if so desired.

Furthermore, owing to the pivotal arrangement of the finger-receiving member or guard, the shank of the needle has a free 65 movement with relation to the forefinger of the operator, thus by means of such free movement permitting of a free and wider scope of movement of the working point or tip of the needle with relation to the work. 70

Other objects of the present invention not at this time more particularly enumerated will be clearly understood from the following detailed description of the present invention. 75

With the various objects of the present invention in view, the said invention consists, primarily, in the novel crochet-needle hereinafter more fully set forth; and, the said invention consists, furthermore, in the 80 novel arrangements and combinations of the various devices and parts, as well as in the details of the construction of the said parts, all of which will be more fully described in the following specification, and then 85 finally embodied in the clauses of the claims which are appended to and which form an essential part of the said specification.

The invention is clearly illustrated in the accompanying drawings, in which:— 90

Figure 1 is a perspective view of a crochet-needle made according to and embodying the principles of the present invention, said view illustrating in connection with the hand of the operator, the application 95 of the crochet-needle, by means of a pivotally disposed finger-receiving loop or guard, to the forefinger of the hand; and Figure 2 is a top or plan view of the crochet-needle and its pivotally mounted finger-receiving loop or guard, detached from the finger. 100

Figure 3 is a plan or top view of a crochet-needle provided with a modified construction of pivoted finger-receiving member or guard; and Figure 4 is a side elevation of the same. 105

Figure 5 is a plan or top view of a crochet-needle provided with still another modified construction of pivotal finger-receiving member or guard. 110

Similar characters of reference are em-

ployed in all of the said above described views, to indicate corresponding parts.

Referring now to the several figures of the drawings, the reference-character 1 indicates the shank or main stem of the ordinary and general construction of crochet-needle, usually made of a continuous piece of tempered wire, which is formed at its one end-portion with a crocheting tip or point 2, and at a suitable point intermediate said tip or point and the end-portion 3 of the shank or stem the latter is made with the oppositely disposed and suitably shaped flat face-portions 4.

15 Referring now more particularly to Figures 1 and 2 of the drawings, in which is shown one form of pivoted finger-receiving means, the reference-character 5 indicates a guard-carrying plate, made of a substantially thin sheet metal, such as aluminum, which is light in weight but of sufficient strength so as to be rigid. At its forward end-portion, the said plate is made with a pair of oppositely extending projections or ears 6 and 7, suitably bent or curled to provide a tubular clamping or holding member, as 8. At its other or rear end-portion, the said plate 5 is made with a laterally extending side-member, as 9, formed at or near its free end with a laterally extending and downwardly curved member 10, said member 10 also terminating at its edge in an upwardly projection guide-flange, as 11. Extending in an upward direction of the said guard-plate 5 is a pivot-post or pin 12 upon which is pivotally or oscillatorily mounted a finger-receiving member or guard which consists, essentially, of a suitably shaped base 13 formed at its opposite edges with thin resilient wings 14, said wings being suitably curved in opposite directions, and terminating toward each other, as at 15. From an inspection of said Figures 1 and 2 of the drawings, it will readily be seen, 45 that the shank or stem of the needle can be easily inserted in a positively clamped or held relation with the tubular member 8 and with the curved retaining member 10 and its guide-flange 11, with the flat face-portion 4 of the shank or stem being located between members 8 and 10, substantially as shown, and the parts being securely held in their assembled relation by the frictional contact of the side-portions of the shank or stem with the interior surface-portions of the tubular member 8 and the curved member 10 and its flange 11, as will be clearly evident.

60 The base 13 and its resilient wings 14 form a tubular element for embracing the user's finger, the wings thus forming a finger-receiving socket which will expand or contact according to the size of the finger, so that the crochet-needle may be readily and effectively used, without requiring the shank of

the needle to be grasped or held between the thumb and fore-finger, thereby preventing cramping of the operator's hand as is now so often the case with the common straight form of crochet-needle.

Furthermore, the pivotal arrangement of the finger-receiving member or guards, permits the needle to be adjusted in its operative position to the forefinger of either the right or left hand, thus enabling the use of 75 the needle by both right-handed and left-handed persons.

In Figures 3 and 4, is illustrated a slightly different construction of base for attaching the pivoted finger-receiving member or guard to the shank or stem of the needle.

80 The attaching means in this construction comprises a flat, or other suitably shaped plate, as 16, which is slightly downwardly bent, as at 17, to provide a holding or retaining member 18, curved at its one end, as at 19, and is then doubled upon itself as at 20, in a manner, as indicated in Figure 85 4 of the drawings. In the curved edge 17 90 is a perforation or opening 23, the members 18 and 20, being preferably formed with the outwardly extending portions 21 and 22, also arranged to provide a receiving socket 95 for maintaining a frictional holding engagement of the plate 16 upon the shank or stem of the needle, when the working end-portion of the latter has been inserted through the hole or perforation 23, and when the tapering edges of the flattened part of the shank 100 or stem are forcibly brought into holding contact with the wall-portions which provide the boundary of the said hole or perforation 23, as will be clearly understood from an inspection of said Figure 3 of the 105 drawings.

At its rear end-portion, the said plate 16 is also provided with a pivot-post or pin 24 upon which is pivotally or oscillatorily mounted a finger-receiving member or guard 110 which consists, essentially, of a suitably shaped base 25 formed at its opposite edges with thin resilient wings 26, said wings, as in the construction shown in Figures 1 and 2 of the drawings, being suitably curved in 115 opposite directions, and terminating toward each other, as at 27. Thus, the plate 16 is provided with a pivoted finger-receiving member or guard of the same construction and for the same purposes as the finger-receiving member or guard heretofore described in connection with the construction 120 illustrated in said Figures 1 and 2 of the drawings.

125 In lieu of either of the construction shown in said Figures 1 to 4 inclusive, and described in the foregoing specification, the flattened portion 4 of the shank or stem of the crochet-needle may be provided with a pivot-post or pin 28, the plates 9 and 16 and 130

the parts connected therewith being dispensed with, as indicated in Figure 5 of the drawings. In this construction, there is pivotally or oscillatorily mounted upon said 5 pivot-post or pin, for the same purposes hereinabove described, a finger-receiving member or guard, consisting of a suitably shaped base 29 formed at its opposite edges with thin resilient wings 30, said wings 10 being suitably curved in opposite directions, and terminating toward each other, as at 31.

From the foregoing description of the present invention it will be clearly evident that a cheap and simply constructed as well 15 as an effectively operating crochet-needle has been produced, the pivotal arrangement of the finger-receiving element or guard, readily permitting the use of the same by persons working with either the right hand 20 or with the left hand.

Furthermore, the pivotal arrangement of the finger-receiving loop permits the needle to be used in a swinging or oscillatory manner with relation to the forefinger, so that 25 the needle-point may be variously used upon the work.

Also, the arrangement of the various parts as described in the foregoing specification and as illustrated in the accompanying 30 drawings, is extremely simple and efficient, thus producing a crochet-needle which can be readily and conveniently used by the operator, without cramping the hand or the forefinger and thumb, as so often happens 35 with needles of the usual and common straight shanks or stems, which necessitate the needle being held with more or less force between the forefinger and thumb.

While in the foregoing I have described 40 the present invention as applied to the shank or stem of a crochet-needle, it will be understood that the principles of the invention may be applied to shanks or stems of the various kinds, adapted for use to numerous 45 purposes other than crochet-work.

I am also aware, that changes may be made in the general arrangements and combinations of the various devices and parts, as well as in the details of the construction, 50 of the said parts, without departing from the scope of the present invention as set forth in the foregoing specification, and as defined in the clauses of the claims which are appended to the said specification. 55 Hence, I do not limit my present invention to the exact arrangements and combinations of the devices and parts, as described in the said specification, nor do I limit myself to the exact details of the construction of the 60 said parts, as illustrated in the accompanying drawing.

I claim:—

1. In combination with a shank or stem adapted for use as a crochet-needle, or the 65 like said shank being provided with flat-

tened portions, a finger-receiving element disposed upon one of said flat portions, and a means of pivotal connection between said shank or stem and the said finger-receiving element for oscillating said finger-receiving 70 element upon said flat portion.

2. In combination with a shank or stem adapted for use as a crochet-needle, or the like said shank being provided with flattened portions, a finger-receiving element 75 disposed upon one of said flat portions consisting of a base and a pair of resilient wings extending from the opposite edges of said base, said wings being curved in opposite directions and terminating toward each 80 other, and a means of pivotal connection between said shank or stem and the base of said finger-receiving element for oscillating said finger-receiving element upon said flat portion. 85

3. In combination with a shank or stem adapted for use as a crochet-needle, or the like said shank being provided with flattened portions, a carrier-plate mounted upon one of said flat portions of said shank or 90 stem, a finger-receiving element located above said carrier-plate and a means of pivotal connection between said carrier-plate and the said finger-receiving element for oscillating said finger-receiving element upon 95 said carrier-plate.

4. In combination with a shank or stem adapted for use as a crochet-needle, or the like said shank being provided with flattened portions, a carrier-plate mounted upon 100 one of said flat portions of said shank or stem, a finger-receiving element located above said carrier-plate, said finger-receiving element consisting of a base and a pair of resilient wings extending from the opposite edges of said base, said wings being curved in opposite directions and terminating toward each other, and a means of pivotal connection between said carrier-plate and the base of said finger-receiving 110 element for oscillating said finger-receiving element upon said carrier-plate. 105

5. In combination with a shank or stem adapted for use as a crochet-needle, or the like said shank being provided with flattened portions, a carrier-plate mounted upon one of said flat portions of said shank or 115 stem, a pivot-post extending upwardly from said carrier-plate, a finger-receiving element located above said carrier-plate, said finger-receiving element consisting of a perforated base for pivotally mounting the same upon said post, and a pair of resilient wings extending from the opposite edges of said base, said wings being curved in opposite directions and terminating toward each other. 120

6. In combination with a shank or stem adapted for use as a crochet-needle, or the like said shank being provided with flattened portions, a carrier-plate comprising a 130

main body, a tubular holding member at one end of said body, and a receiving member at the other end of said body provided with an upwardly projecting guide-flange, 5 all arranged for receiving said shank or stem and for mounting said carrier-plate upon one of said flat portions of said shank or stem, a finger-receiving element located above said carrier-plate, and a means of 10 pivotal connection between said carrier-plate and the said finger-receiving element for oscillating said finger-receiving element upon said carrier-plate.

7. In combination with a shank or stem 15 adapted for use as a crochet-needle, or the like said shank being provided with flattened portions, a carrier-plate comprising a main body, a tubular holding member at one end of said body, and a receiving member at the other end of said body provided with an upwardly projecting guide-flange, 20 all arranged for receiving said shank or stem and for mounting said carrier-plate upon one of said flat portions of said shank 25 or stem, a finger-receiving element located above said carrier-plate, said finger-receiving element consisting of a base and a pair of resilient wings extending from the opposite edges of said base, said wings being 30 curved in opposite directions and terminating toward each other, and a means of pivotal connection between said carrier-plate

and the base of said finger-receiving element for oscillating said finger-receiving element upon said carrier-plate.

8. In combination with a shank or stem adapted for use as a crochet-needle, or the like said shank being provided with flattened portions, a carrier-plate comprising a main body, a tubular holding member at 35 one end of said body, and a receiving member at the other end of said body provided with an upwardly projecting guide-flange, all arranged for receiving said shank or stem and for mounting said carrier-plate 40 upon one of said flat portions of said shank or stem, a pivot-post extending upwardly from said carrier-plate, a finger-receiving element located above said carrier-plate, said finger-receiving element consisting of a perforated base for pivotally mounting the same upon said post, and a pair of resilient 45 wings extending from the opposite edges of said base, said wings being curved in opposite directions and terminating toward each 50 other.

In testimony that I claim the invention set forth above I have hereunto set my hand this 23rd day of December, 1920.

SAMUEL M. RIKER.
